Inventor,
G. R. Watson, by
G. Kennedy,
Attorney.

UNITED STATES PATENT OFFICE.

GEORGE R. WATSON, OF WATERLOO, IOWA, ASSIGNOR TO ARMSTRONG MANUFACTURING COMPANY, OF WATERLOO, IOWA.

DRILL BIT.

Application filed June 19, 1924. Serial No. 720,976.

To all whom it may concern:

Be it known that I, GEORGE R. WATSON, a citizen of the United States of America, and a resident of Waterloo, Blackhawk County, 5 Iowa, have invented certain new and useful Improvements in Drill Bits, of which the following is a specification.

My invention relates to improvements in drill-bits, and the object of my improvement 10 is to supply for use in efficiently drilling holes in rock formations a drill whose bit is so shaped as to operate as a reaming cutter and crushing means.

This object I have accomplished by the 15 means which are hereinafter described and claimed, and which are illustrated in the accompanying drawings, in which Fig. 1 is a side elevation of my improved drill and bit, with a part broken away, and Fig. 2 is an 20 elevation thereof taken at an angle of ninety degrees from the elevation shown in said Fig. 1. Fig. 3 is a plan of the bit end or face, and Fig. 4 is a cross-section of the drill body taken on the broken line 4—4 of said 25 Fig. 1.

The drill shank or top 1 has an upwardly projecting coned threaded boss 2 to be removably received in a threaded counterpart socket in the lower end of a drill-stem. The 30 body 3 is cylindrical, and has at opposite sides the longitudinal grooves 6 between flattened edge parts 5, said grooves terminating below in an anticlinal cutter ridge 7—8, and being narrowed at 10 in traversing the 35 lower widened part 4 of the drill, to supply

reaming cutters. The bottom face of the drill at 9 is coned at a small angle of hollowing toward the middle point of the arcuate ridge 7—8.

In operation, in the raising and dropping 40 of the drill, the edge angles of the parts 4 at 10 cut and ream the wall of the drill-hole cylindrically, the interspaces at 10 being too narrow to make flat places in the wall or on the other hand to allow the drill to be influenced in its movements by any such flat spots as might occur due to hard places in the rock. The coned hollow and crushing face 9 of the bit centers the bit, and the dome of rock is disintegrated at the top by the ridge 45 7—8.

Having described my invention, what I claim as new, and desire to secure by Letters Patent, is:

1. A drill-bit having a longitudinally 55 grooved body and a crushing reaming head of larger diameter, the crushing face of said head being upwardly hollowed and having a cross groove uniting the lower ends of the other grooves at a diametrical ridge. 60

2. A drill-bit having a bit with an upwardly conically hollowed crushing face, and having opposite hollows which cross the crushing face to provide between the separated parts of the crushing face a medial 65 ridge, positioned at the apex of the conical hollow.

Signed at Waterloo, Iowa, this 15th day of May, 1924.

GEORGE R. WATSON.
